ATTORNEY

FIG. 2

UNITED STATES PATENT OFFICE.

PETER BOANO, OF SAN FRANCISCO, CALIFORNIA.

CHAFING SHIELD.

Application filed July 6, 1925. Serial No. 41,816.

One object of my invention is to provide a chafing shield that will prevent the clothing from irritating the male genital organs.

Further objects of my invention will hereinafter appear.

The invention consists of the construction, combination and arrangement of parts as hereinafter more fully described and claimed, having reference to the accompanying drawing, in which:

Figure 1 is an elevation of the chafing shield complete and ready to apply.

Figure 2 is a section on "A—A" of Figure 1 showing construction of chafing shield.

Figure 3 is an elevation of the shield sheet.

Figure 4 is a section on "B—B" of Figure 3 showing construction of shield sheet.

Figure 5 is an elevation of the holders.

Referring to the drawings in detail:

1 is the envelope, made of some soft material.

2 are button holes worked in envelope so that the holders 3 that are attached to sheet 4 may protrude thru the envelope for attaching chafing shield to clothing.

5 is the lower end of the envelope which is left open. The two holders 6 merely drop thru the opening 5.

The shield sheet 7 consists of a number 20 of sheets of fine waxed paper held together by means of an adhesive material 8 doubled around the edges. The inner sheets are held by means of scallops 9 cut around the edges of the outer sheets. The adhesive material 35 8 therefore may hold all sheets the same.

Holes 11 are provided so that the holders 3 may be tied to the shield sheet. In tying, one end 12 of holder is passed thru hole 11. End 13 of holder is then passed thru hole 40 14 and drawn taut.

The shield envelope is a little larger than the shield sheet, so that the movement of the clothing may move only its outer part, and is open at the bottom so as to change 45 the shield sheet when required. As the shield should be attached straight up and a little loose, it may tend to slide a little toward one side or the other. To prevent this, the side holder serves to hold it in 50 place.

The chafing shield is useless in acute cases of gonorrhœa and similar cases where there is much discharge because if it included absorbent or nonabsorbent material, it would 55 cause heat when sitting. In such cases, it

will do, as soon as the acute stage of the disease is over.

A chafing shield for said purposes and an explanation that it is necessary, should go together. What is self-evident and provable 60 follows:

The combined action of the legs and body move the clothing enough to irritate, except when walking too slow. The abdomen or upper part of the body lets down the clothing a little and when the leg is far back, pulls it up again. If the suspenders are strong, or the clothing too tight, or both, when the free leg moves back, it moves the clothing on the other, sideways. In some cases, the irritation happens both ways. Tight clothing also causes pressure when sitting, and pressure is a form of irritation.

Both the rubbing of the clothing and tight clothing may not mean anything when the sex organs are in a perfect state of health, but when any organ of the body is diseased or weak, its sensitiveness is increased, its inner parts shrink at any irritation or pressure, as if in an effort to shun it and consequently weaken or fail to strengthen. For this reason a chafing shield is indispensable as a bandage for wounds, to be used until cured. Whatever prevents only one source of irritation, such as in the case of a chafing shield, may be only a small part of the remedy, especially in germ cases, but it is indispensable to that extent. Whatever irritates or hurts, mental or physical, prevents a cure and therefore whatever prevents any irritation, is both curative and indispensable.

As the disease germs in any one part of any organ affect other parts of the organ and invariably other organs as well, and as the rubbing of the clothing affects only some parts of the genitourinary system, a chafing shield cannot mean that it will cost less than usual to get a cure, but is rather an additional expense. Whether a disease involves six tenths or seven tenths of certain organs, for instance, the difference of one tenth is not enough for a physician to reduce the time and method in treating the case. For these reasons, a chafing shield 100 does not even make it easier to get a real cure, but it makes it more possible.

Since it is probable that the clothing does not irritate enough in some cases, the chafing shield is required to consist of light 110

and harmless material, so that if a patient should feel that it is not necessary in his case, say, after a few weeks, he may discard it and be none the worse for it.

5 Having thus described my invention, what I claim and desire Letters Patent for is:

A chafing shield for preventing the male

genital organs from rubbing against the clothing, comprising a sheet of waxed paper, an envelope of soft material surrounding ¹⁰ said sheet and means for attaching the shield to the clothing.

PETER BOANO.
